(57) **CLAIM**

I claim the ornamental design for the mixing bowl, as shown and described.

DESCRIPTION

FIG. 1 is a top perspective view of a mixing bowl, showing my new design.

FIG. 2 is a top view of the mixing bowl.

FIG. 3 is a front view of the mixing bowl, the rear view being identical; and,

FIG. 4 is a left side view of the mixing bowl, the right side view being identical.

The bottom view is unornamented and not shown.
